FUEL FEED APPARATUS FOR INTERNAL COMBUSTION ENGINES

Filed May 19, 1926.

UNITED STATES PATENT OFFICE.

BASIL H. SAVAGE, OF LOS ANGELES, CALIFORNIA, ASSIGNOR OF FOUR-SIXTEENTHS TO NORMAN B. BENNETT, ONE-SIXTEENTH TO OSCAR F. BOWMAN, FOUR-SIXTEENTHS TO MANSELL A. DAVIS, AND TWO-SIXTEENTHS TO HARRY B. NEWCOMB, ALL OF LOS ANGELES, CALIFORNIA.

FUEL-FEED APPARATUS FOR INTERNAL-COMBUSTION ENGINES.

Application filed May 19, 1926. Serial No. 110,132.

This invention relates to vacuum fuel feed systems for internal combustion engines. Apparatus of this class usually comprises a main tank or reservoir having an outlet 5 for the flow of liquid by gravity to the carburetor of the engine, a vacuum tank or auxiliary reservoir having a valve-controlled outlet, through which liquid may flow to the main reservoir, and also having an inlet 10 for liquid fuel, a suction outlet adapted to be connected to the intake of the engine, and a vent opening. A float within the auxiliary reservoir operates valves which alternately connect the auxiliary reservoir 15 to the suction intake of the engine and to the atmosphere. The valves are usually actuated by levers which are moved positively by the float for a certain distance and are then thrown by springs to their seated or unseated positions. Thus, the valves will be 20 operated to close the suction outlet and to open the air vent after a determined amount of fuel has been drawn into the auxiliary reservoir, and the valves will be operated to open the suction outlet and close 25 the air vent after the same amount of fuel has been discharged from the auxiliary reservoir into the main reservoir.

In carrying out my invention, instead of 30 employing springs to effect the quick throw of the valves, and to retain them in the positions to which they are moved until a determined amount of liquid is drawn into or discharged from the auxiliary reservoir, I 35 provide means whereby the buoyancy of the float is increased, by the admission of air into the float, after a determined amount of liquid has been drawn into the auxiliary reservoir, so that the float quickly closes the 40 suction outlet and keeps this outlet closed until the determined amount of liquid is discharged into the main reservoir, when the float opens the suction outlet and closes the air inlet, whereupon the buoyancy of the float 45 is decreased by the exhaustion of air from the float, and the latter will not rise to close the suction inlet until the determined amount of liquid has been drawn into the auxiliary reservoir.

50 In vacuum fuel feed systems, when the fuel is being drawn into the auxiliary reser-

voir, rich vapors arise in the reservoir and are carried through the suction outlet to the intake of the engine, and this rich mixture interferes with the uniform operation of the 55 engine. In order to overcome this difficulty, I provide means for admitting air directly from the atmosphere into the suction outlet of the auxiliary reservoir, and this air mingles with the vapors passing to 60 the intake and makes a diluted mixture such as the engine requires.

The invention involves also a novel form of suction operated discharge valve for controlling the passageway between the two 65 reservoirs.

In the accompanying drawing,

Fig. 1 is a central vertical section through the apparatus;

Fig. 2 is a similar view through a part 70 of the apparatus, partly broken away, showing the suction outlet closed and the air vent open;

Fig. 3 is a section on the line 3—3 of 75 Fig. 1;

Fig. 4 is a top plan view of the valve mechanism for controlling the passageway between the reservoirs; and,

Fig. 5 is a side view of the plunger shown in Figs. 1 and 4.

Referring to the drawing, *a* indicates the main reservoir of the fuel feed system, having a discharge outlet 1, adapted for connection to the carburetor of the engine, and *b* indicates an auxiliary reservoir arranged 85 within the main reservoir and having a valve controlled fitting *e*, through which liquid may be discharged into said main reservoir. The fitting *e* comprises a tube 2, extending downwardly through a central opening in 90 the bottom 3 of the auxiliary reservoir and sealed in said opening, and a cylindrical cup 4, the lower edge of which rests upon the bottom of the reservoir. This cup forms a cylindrical wall surrounding the outlet passageway. With this arrangement, it will be evident that liquid from the auxiliary reservoir cannot discharge into the main reservoir except by overflowing the upper edge 95 of the cup, and that some liquid will be held 100 in the auxiliary reservoir at all times in the space surrounding the cup. A hollow

plunger f , comprising a cap piece 5 and an angular flange 5^a , fits over the cup 4, and to the central part of this plunger is secured a valve stem 6, which extends through the cup and tube and has at its lower end a valve 7, which is adapted to seat against the lower end of the tube when the plunger 5 is lifted upwardly. The flange of the plunger has its lower edge cut away at the angles between its faces, as shown at 5^b , and in the top of the plunger is a small perforation 8. When the plunger and valve are in their lower positions, shown in the drawing, the lower edge of the plunger rests upon the bottom of the auxiliary reservoir within the liquid which is retained in the reservoir by the cup 4, and the top of the plunger is held slightly above the upper edge of the cup. As the wall of the cup is circular and the surrounding wall 20 of the plunger is angular, the liquid may rise, through the cut-away portion 5^b , in the spaces 9 between the plunger and the cup to the upper edge of the latter. The liquid surrounding the cup maintains a seal against the flow of air from the cup through the passageways 9 into the auxiliary reservoir.

The main reservoir is always at atmospheric pressure, and when the pressure in the auxiliary reservoir is lowered by the suction of the engine, an upward pressure is exerted against the underside of the plunger and the latter lifts quickly and closes the valve 7, and thereafter, until the pressure in the auxiliary chamber is restored to normal, the valve will be held against its seat by the atmospheric pressure against the underside of the valve. The plunger and valve will be lifted by air entering the tube 2, if the level of the liquid in the main reservoir is below the end of said tube, as it may be when the apparatus is first primed, or the plunger and valve may be lifted by the upward flow of liquid in the tube and cup if the level of the liquid in the main reservoir is above the level of the cup, as it generally is. When the pressure in the auxiliary reservoir becomes normal, the plunger and valve drop by gravity and liquid can then flow through the passageways 9 and through the cup and tube into the main reservoir until the level of the liquid in the auxiliary chamber is lowered to such an extent as to cause the float to open the suction inlet, as herein-after described, when the plunger will lift and close the valve 7, as before. The vent 8 is a relatively small orifice for preventing air from accumulating in the plunger, which air would cause the plunger to float. The leakage of air through this restricted orifice does not interfere with the lifting of the plunger by atmospheric pressure when the pressure in the auxiliary chamber is lowered.

The auxiliary reservoir b has an opening 12 at its top, adapted for connection to the fuel source, which, in an automobile, is a

tank usually located below the vacuum feed apparatus. The auxiliary reservoir also has a suction outlet 13, adapted for connection to the intake manifold of the engine. Within the auxiliary reservoir is arranged a float c , which is open at the bottom and which is mounted upon a tubular stem 14, passing axially through the float. As shown, the top of the float is secured to the stem and a bell-shaped member 15 has its lower edge 15^a secured to the lower edge of the float, and this member projects upwardly within the float and has an opening through which the valve stem 14 extends. The member 15 is secured to the valve stem and serves as a centering means for the stem as well as a strengthening means for the float. The member 15 has openings 15^b near its lower edge to permit the liquid fuel to flow upwardly into the float. The member 15, which is made of sheet metal, has a perforation 16 in its upper part and the float has a perforation 17, which is shown slightly lower than the perforation 16. The purpose of these perforations will be presently explained.

The valve stem is slidable in an opening 19^a in a plug 19, which is threaded into the passageway 13, the opening 19^a being of sufficient diameter to permit the valve rod to move freely therein and also to permit the suction of the engine to exhaust the auxiliary reservoir through said enlarged opening. A valve seat 20 is threaded into the suction outlet and this seat has a plurality of openings 21 and a central downwardly projecting pin 22, which pin is in line with the bore 14^a in the valve stem. When the valve stem is raised, the pin first enters the bore in the stem and closes the same, and the end of the stem then engages the valve seat and closes the several ports 21. The combined cross-sectional area of these ports is much greater than the cross-sectional areas of the bore in the stem and of the opening in the plug surrounding the stem.

A fitting d , arranged within the reservoir b , has a vent passageway 23 which extends downwardly through the reservoir and thence upwardly under the float, and the lower end of the valve stem is slidably mounted in the upwardly turned portion 23^a of the passageway. The valve stem fits closely within the vent passageway and has an annular groove 24 which is closed by the wall of the passageway when the float is in its lower position. Perforations 25 in the valve stem connect the groove 24 with the bore 14^a in the stem. A collar 26, secured to the stem, rests upon the upwardly projecting part d' of the fitting d when the float is down and forms a stop for limiting the downward movement of the float. When the float is moved upwardly and before the upper end of the valve stem reaches its seat, the groove 24 in the lower end of the stem ex-

tends above the part d' of the fitting d , as shown in Fig. 2, and thus the air from the vent passageway can flow freely through the openings 25 into the float beneath the dome-shaped member 15. The fitting d has a threaded extension d^2 which extends through the top plate 27 of the apparatus, and a nut 28, threaded on to the extension d^2 , secures the fitting to the plate. This nut has an opening 29, which forms a continuation of the vent passageway. A tubular screw 30, extending through the wall of the reservoir b and into the fitting d , has a passageway 31 which connects the interior of the reservoir a with the vent passageway 23. Thus, atmospheric pressure is maintained in the reservoir a at all times. The two reservoirs are suitably secured together at their upper ends, in an airtight manner.

In operation, assuming the apparatus to have been initially primed with fuel, the suction of the engine lowers the pressure in the reservoir b , and owing to this lower pressure the plunger 5 lifts and closes the valve 7 and liquid fuel is drawn into this reservoir through the inlet 12. As the fuel enters the reservoir b rich vapors arise and these vapors will be drawn through the passageway 19^a to the intake of the engine. These vapors are, however, diluted by air flowing through the bore 14^a of the valve stem from the atmosphere and also, to a slight extent, by air drawn from the float through the opening 17. The opening 17 in the float is always above the liquid level and air, which may be drawn from the float, will pass through the vapor to the passageway 19^a, but not through the liquid. Any air escaping from the passageway 23^a past the valve stem, when the latter is down, will be drawn through the opening 16 and thence through the opening 17 and the passageway 19^a, and will then pass to the intake of the engine. The suction lowers the air pressure within the float so that its buoyancy is lowered when the reservoir is exhausted, whereas, if the float were entirely enclosed its buoyancy would remain the same. As the liquid accumulates in the reservoir b , the float c will rise gradually until the annular groove 24 in the valve stem rises partly above the upwardly projecting part d' of the fitting d , when there will be a free escape of atmospheric air from the vent passageway into the float, and this will suddenly increase the buoyancy of the float. At this time, the upper end of the valve stem is near its closed position and the float will quickly move upward, causing the bore 14^a to be closed by the pin 22, and this will be immediately followed by the closure of the ports 21 by the end of the stem. When the pin 22 closes the bore 14^a, the flow of air from the atmosphere through the vent passageway to the intake of the engine is cut off, and when the

ports 21 are closed the suction through the passageway 19^a ceases. The admission of air to the reservoir b , through the passageway 23 and the ports 25, breaks the vacuum in said reservoir and the valve 7 then drops to open position, thus opening the passageway between the two reservoirs so that liquid may flow from one to the other. As the buoyancy of the float is increased by the admission of air to its interior, the float will remain in raised position, keeping the suction outlet closed, until the liquid level in the auxiliary reservoir is lowered to a considerable extent through discharge of the liquid from the reservoir b . When the liquid in the reservoir b has lowered to the point where the float starts to move downward, the suction outlet is opened by the float, the valve 7 closes and the pressure in the float as well as in the reservoir b is lowered by the suction of the engine. The buoyancy of the float is thus decreased and it drops to its lowermost position, closing the air vents 25 and opening the upper end of the valve rod, permitting a limited amount of air to flow through the valve rod and mingle with the vapors passing to the intake of the engine, and permitting air to be drawn from the float through the port 17 and passageway 19^a as before. Thus, there cannot be an excessive accumulation of air in the float at any time. When the suction outlet is opened, the lowering of the pressure in the reservoir b causes liquid to be drawn from the fuel source into the auxiliary reservoir, and when the liquid reaches a certain level the float rises and controls the valves as before described.

What I claim is:

1. In a fuel feed system for internal combustion engines, a main reservoir having an outlet for the flow of liquid fuel to the carburetor, an auxiliary reservoir having an outlet for the flow of liquid into said main reservoir, a valve adapted to keep the latter outlet closed while the pressure in the auxiliary reservoir is below atmospheric pressure, said auxiliary reservoir having an inlet for liquid fuel adapted to be connected to the source of fuel supply and having a suction outlet adapted for connection to the intake of the engine, a hollow float in the auxiliary reservoir, a valve operable by the float during its upward movement for closing the suction outlet, and means for admitting air into said float to increase its buoyancy, near the end of its upward movement.

2. In a fuel feed system for internal combustion engines, a main reservoir having an outlet for the flow of liquid fuel to the carburetor, an auxiliary reservoir having an outlet for the flow of liquid into said main reservoir, a valve adapted to keep the latter outlet closed while the pressure in the aux-

iliary reservoir is below atmospheric pressure, said auxiliary reservoir having an inlet for liquid fuel adapted to be connected to the source of fuel supply and having a suction outlet adapted for connection to the intake of the engine, a hollow float in the auxiliary reservoir, a valve operable by the float during its upward movement for closing the suction outlet, and means for admitting air 10 from the atmosphere into said float after it has started to move upward.

3. In a fuel feed system for internal combustion engines, a main reservoir having an outlet for the flow of liquid fuel to the carbureter, an auxiliary reservoir having an outlet for the flow of liquid into said main reservoir, a valve adapted to keep the latter outlet closed while the pressure in the auxiliary reservoir is below atmospheric pressure, said auxiliary reservoir having an inlet for liquid fuel adapted to be connected to the source of fuel supply and having a suction outlet adapted for connection to the intake of the engine, an open-bottomed float 25 in the auxiliary reservoir, a passageway leading from the atmosphere to a point beneath the float, a valve operable by the float for establishing communication between the passageway and float when the latter moves upward and for cutting off communication 30 between the passageway and float when the float moves downward, and a valve, also operable by the float, for closing and opening the suction outlet.

35 4. In a fuel feed system for internal combustion engines, a main reservoir having an outlet for the flow of liquid fuel to the carbureter, an auxiliary reservoir having an outlet for the flow of liquid into said main reservoir, a valve adapted to keep the latter outlet closed while the pressure in the auxiliary reservoir is below atmospheric pressure, said auxiliary reservoir having an inlet for liquid fuel adapted to be connected to the source of fuel supply and having a suction outlet adapted for connection to the intake of the engine, an open-bottomed float 45 in the auxiliary reservoir, said float having a vent in its side wall, and means controlled by the upward movement of the float for closing the suction outlet and for admitting air into the float.

50 5. In a fuel feed system for internal combustion engines, a main reservoir having an outlet for the flow of liquid fuel to the carbureter, an auxiliary reservoir having an outlet for the flow of liquid into said main reservoir, a valve adapted to keep the latter outlet closed while the pressure in the auxiliary reservoir is below atmospheric pressure, said auxiliary reservoir having an inlet for liquid fuel adapted to be connected to the source of fuel supply and having a suction outlet adapted for connection to the intake 55 of the engine, an open bottomed float in the

auxiliary reservoir, said flat having a vent in its side wall above the line to which the liquid rises around the float, and means controlled by the upward movement of the float for closing the suction outlet and for admitting air into the float. 70

6. In a fuel feed system for internal combustion engines, a main reservoir having an outlet for the flow of liquid fuel to the carbureter, an auxiliary reservoir having an outlet for the flow of liquid into said main reservoir, a valve adapted to keep the latter outlet closed while the pressure in the auxiliary reservoir is below atmospheric pressure, said auxiliary reservoir having an inlet for liquid fuel adapted to be connected to the source of fuel supply and having a suction outlet adapted for connection to the intake of the engine, an open-bottomed float in the auxiliary reservoir, a passageway 85 leading from the atmosphere to a point beneath the float, a tubular stem secured to the float and connecting said passageway with the suction outlet, said stem adapted, when the float is raised, to admit air from said passageway into the float and to close the suction outlet. 90

7. In a fuel feed system for internal combustion engines, a main reservoir having an outlet for the flow of liquid fuel to the carbureter, an auxiliary reservoir having an outlet for the flow of liquid into said main reservoir, a valve adapted to keep the latter outlet closed while the pressure in the auxiliary reservoir is below atmospheric pressure, said auxiliary reservoir having an inlet for liquid fuel adapted to be connected to the source of fuel supply and having a suction outlet adapted for connection to the intake of the engine, a valve seat in the suction outlet having a port and a downwardly projecting pin, an open-bottomed float in the auxiliary reservoir, a passageway leading from the atmosphere to a point beneath the float, a tubular stem secured to the float and connecting said passageway with the suction outlet, said stem adapted, when the float is raised, to be closed by said pin and to close said port and also to admit air from said passageway into the float. 100 105 110 115

8. In a vacuum fuel feed system for internal combustion engines, a main reservoir, an auxiliary reservoir having an outlet for the flow of liquid into said main reservoir, a wall surrounding said outlet and projecting above the bottom of the auxiliary reservoir, a plunger comprising a cap piece and a flange extending over and around said wall, and a valve attached to said plunger and adapted to close said outlet when the plunger is lifted. 120 125

9. In a vacuum fuel feed system for internal combustion engines, a main reservoir, an auxiliary reservoir having an outlet for the flow of liquid into said main reservoir, 130

a wall surrounding said outlet and projecting above the bottom of the auxiliary reservoir, a plunger extending over and around said wall, said plunger having a relatively small vent opening, and a valve attached to said plunger and adapted to close said outlet when the plunger is lifted.

10. In a vacuum fuel feed system for internal combustion engines, a main reservoir, an auxiliary reservoir having an outlet for the flow of liquid into said main reservoir, a wall surrounding said outlet and projecting above the bottom of the auxiliary reservoir, a plunger comprising a cap extending over said wall and a flange extending downwardly around said wall, said flange and wall having a passageway therebetween, and a valve attached to said plunger and adapt-

ed to close said outlet when the plunger is lifted.

11. In a vacuum fuel system for internal combustion engines, a main reservoir, an auxiliary reservoir having an outlet for the flow of liquid into said main reservoir, a circular wall surrounding said outlet and projecting above the bottom of the auxiliary reservoir, a plunger comprising a cap extending over said wall and an angular flange, extending downwardly around said wall, said flange having its lower edge notched, and a valve attached to said plunger and adapted to close said outlet when the plunger is lifted.

In testimony whereof I hereunto affix my signature.

BASIL H. SAVAGE.
